GEORGE W. BLAIR, OF MISHAWAKA, INDIANA, ASSIGNOR TO MISHAWAKA RUBBER & WOOLEN MANUFACTURING COMPANY, OF MISHAWAKA, INDIANA, A CORPORATION OF INDIANA

FLEXIBLE REENFORCING

Application filed May 21, 1925. Serial No. 31,767.

My invention has reference to the reenforcing of flexible articles, as for example overshoes and other types of footwear, so as to avoid sharp bends, where flexing occurs, and my invention is particularly useful in connection with fasteners of the quick operating type, wherein opposed fastener members are interlocked and released by movement of a cam member or slider therealong as it serves, to prevent excessive bending that might injure or impair the fastener members.

It has become quite an extensive practice to make articles of footwear, such as overshoes, with a quick operating fastener extending down the front and comprising opposed series of fastener elements, on the forward edges of the side portions or quarters of the overshoe, which are interlocked and released by movement of a slider therealong. A constant bending takes place at the front of the overshoe in the act of walking, which, of course, causes a corresponding constant bending of the fastener. If the overshoe fits fairly close this bending of the fastener is not severe. However, overshoes of this type are usually made without any provision for adjusting the size of the upper, and as it is impracticable to put them out with a variety of sizes of uppers, it oftentimes occurs that the upper fits somewhat loosely around the leg. In such cases, the extra fullness causes the portion of the upper at the bend to buckle inwardly in walking and imposes a rather sharp bending strain on the fastener and also tends to form an objectionable crease or wrinkle at the bend. This bending and wrinkling tendency is also made more pronounced in high top shoes or overshoes because the upper is usually made of a soft material and the taper of the leg and the working of the muscles causes some downward crowding action on the upper. Aside from the foregoing there are other occasions where a decided bend is given to the front of the overshoe and the fastener, as for example, in stooping.

In quick operating fasteners of the type referred to above, the fastener elements are arranged close together in series in a flexible manner, as for example, by mounting sep-

arate elements on a tape or stringer or by forming the elements as coils or loops of a coiled element or spiral spring, and excessive or sharp bending of the fastener tends to jam the elements together at the inner side of the bend and impose undesirable strains thereon, and also in some cases allows the interengaged elements to slip sidewise out of engagement. Moreover if there is a constant and excessive bending as in the case where the upper fits loosely and buckles inwardly in the act of walking, the fastener may give way under the constant strain and become disarranged or broken.

With my invention I provide reenforcing, along the front portion of the overshoe where excessive bending is likely to occur, which tends to round out or increase the radius of the bend, thereby distributing or extending the bend along a greater length of the fastener and avoiding concentration of the bend within narrow limits involving only a few fastener elements. This reenforcing may be effected by increasing the thickness of portions of the overshoe along the fastener, and in practice I accomplished the result by embodying in portions of the overshoe along the fastener, strips of rubber composition, rubberized fabric or other suitable material which is shaped so that the reenforcing merges into the structure and is unnoticeable.

This reenforcing not only serves the purpose in connection with a quick operating fastener of protecting the latter against injurious bending but also serves to hold the upper portion of the overshoe extended smoothly so as to counteract any downward crowding tendency of the upper portion of the overshoe, and not only improves the appearance of the shoe but also increases the comfort on account of the fact that wrinkling cannot occur. The reenforcing may be advantageously employed, for the latter purpose in overshoes and footwear where a quick operating fastener is not used and may also be used in connection with a quick operating fastener on other articles, besides overshoes and footwear, where excessive bending may occur.

The principal objects of my invention are to avoid excessive or injurious bending of a quick operating fastener; to prevent jamming together or cramping of fastener elements when the fastener is bent; to distribute or extend the bending in a quick operating fastener along a sufficient length of the latter so that the bending strain is not localized or concentrated within narrow limits; to arrange the reenforcing so that it is not discernible; to provide a simple and convenient reenforcing in overshoes or other footwear for holding the upper portion thereof extended and counteracting downward crowding and wrinkling of the upper; to improve the appearance of the shoe and make it more comfortable on the leg and foot; to arrange the reenforcing so that a minimum amount of reenforcing material is required; and in general to improve the construction of overshoes and other footwear and increase the durability of quick operating fasteners.

Referring to the accompanying drawing in which I have, for the purpose of illustration, shown my invention as applied to an overshoe of the type commonly worn by women, Fig. 1 is a perspective view of an overshoe embodying my improvements.

Fig. 2, a fragmentary sectional view on the line 2—2 of Fig. 1.

Fig. 3, a front view of the overshoe tongue with fragmentary portions of the sides and vamp, and

Fig. 4, a longitudinal view, with an intermediate portion broken away, taken on the line 4—4 of Fig. 3.

The overshoe shown in the accompanying drawings which is indicated as a whole at 1 is divided down the front to afford separable side portions 2 and 3 each of which said portions has a fastener member 4 and 5 respectively in the form of an elongated coiled spring secured to the forward edges thereof and adapted to be interlocked and released by movement of a slider 6 therealong. The fastener illustrated is like that of my application Serial No. 757,321 filed December 22, 1924, wherein the individual convolutions of one spring nest quite closely between adjoining convolutions of the other spring, the convolutions of one of the springs, as for example 4, having offsets at the outer ends for affording an interlocking engagement. Other forms of fastener may, however, be used.

A tongue is commonly employed in connection with overshoes of this character, underlying the opening down the front of the overshoe, the tongue in the present case, indicated at 7, being of the bellows type having a portion 8 at each side thereof folded back over the front and secured along the forward edge to the underside of the forward edges of the respective side portions 2 and 3 of the overshoe. This tongue usually consists of a facing 9 and lining 10 both of fabric which are

cemented together or combined by an intermediate thin layer 21 of rubber composition. In my construction a reenforcing or stiffening element is incorporated in this tongue and comprises a strip 11, preferably of rubber composition, although rubberized fabric or other suitable material may be used, and this is cemented or otherwise secured between the facing 9 and lining 10 and extends up and down the front of the overshoe directly underneath the fastener members 4 and 5.

The place or places where bending is likely to occur is in the vicinity of the line 2—2 of Fig. 1 and the reenforcing 11 extends sufficiently above and below this point to include any possible range in which bending may occur. As a matter of fact, I prefer to extend the reenforcing pretty well up to the top of the tongue so as to hold the tongue extended and prevent same creeping downwardly or wrinkling. This strip 11 of reenforcing, is tapered off to a feather edge at each side, as shown in Fig. 2, and at the ends, as shown in Fig. 4, so that there is no irregularity in the faces of the tongue and this reenforcing is molded on the last so that it naturally assumes the required shape to fit over the instep and lower portion of the leg.

Additional reenforcing is also provided in the form of similar strips 12, of rubber composition or other suitable material, which are assembled in the forward edges of the side portions 2 and 3 of the overshoe. In practice it has been found convenient to mount the fastener members on tapes which are in turn secured to the forward edges of the side portions of the overshoe. In the present case a doubled over tape is employed comprising the side portions 13 and 14 with the intermediate portion 15 secured to or engaged around a cord 16 which runs lengthwise through the coiled spring fastener element 4 or 5, and the two side portions of the tape are stitched together as at 17 along the side of the spring fastener element. The reenforcing 12 is preferably cemented or otherwise secured between the side portions 13 and 14 of the tape as shown in Fig. 2 and the facing 18 of the side portion of the overshoe is extended over and secured to the outer face of the tape section 13 while the lining 19 and the back turned edge 20 of the overshoe tongue are secured to the inner face of the tape section 14. It is to be understood, of course, that other form of assembly may be used and that the arrangement of the parts above described is merely illustrative of a form in which I find it desirable to assemble the parts.

The side reenforcing members 12 likewise extend sufficiently above and below the place where bending is likely to occur, approximately in the same manner as the reenforcing 11, and these reenforcing members 12 taper at each side and at the opposite ends to a feather edge so that a smooth surface is presented at

the inner and outer sides of the side portions 2 and 3.

With the above construction the extra thickening of the intermediate portion of the tongue and edges of the side portions 2 and 3 of the overshoe, and the stiffening effect of the elements 11 and 12 prevents any sharp bends occurring at the front portion of the overshoe, as any bend is caused to assume a well rounded form. Consequently excessive or sharp bending of the fastener elements which might injure same is avoided. Moreover the reenforcing elements serve the additional purpose of holding the front of the overshoe extended so that it cannot work downwardly and wrinkle, and the overshoe thus maintains a smooth and neat appearance under constant wear. It is to be understood that sufficient reenforcing or protection of the fastener elements may be obtained by merely using a reenforcing element in the tongue alone or by merely using the reenforcing in the edges of the side portions 2 and 3, although it is preferred to have both the tongue and the edges of the side portions of the overshoe reenforced as this required a less amount of reenforcing in each location. Moreover reenforcing similar to that shown herein may be advantageously used in foot-wear, with other types of fasteners, for holding the upper in the outstretched position and preventing same from slipping downwardly or wrinkling.

While I have shown and described my invention in a preferred form I am aware that various changes and modifications may be made without departing from the principles of my invention the scope of which is to be determined by the appended claims.

40 I claim as my invention:

1. The combination of a flexible article having a wall with an opening, a strip of flexible reenforcing and a mounting tape concealed within and stiffening the marginal portion of the wall along each side of the opening, each mounting tape having an edge portion thereof projecting beyond the respective edge of the wall and provided with a series of fastener elements thereon, and a slider operable along said series of fastener elements for interlocking the series of fastener elements on one side of the opening with the series of fastener elements on the other side of the opening.

55 2. The combination with a flexible article having an opening, a fastener comprising opposed series of interlocking elements for closing said opening, and a slider for interlocking and releasing said opposed elements and having an operating handle at the outer side of the fastener, of a tongue at the inner side of the fastener having a strip of stiffening material extending lengthwise under the juncture line of the opposed series of elements.

60 3. The combination of a fastener comprising

ing opposed series of fastener elements and a slider operable therealong for interlocking and releasing same, said slider having an operating handle at the outer side of the fastener, and a tongue at the inner side of the fastener having a strip of stiffening material extending lengthwise along the juncture line of the fastener to provide a smooth surface along which the slider operates.

4. The combination with a fastener comprising opposed series of fastener elements and a slider operable therealong for interlocking and releasing same, of a tongue having a strip of transversely arched stiffening material extending lengthwise along the juncture line of the fastener to afford a central ridge on which the slider operates.

5. The combination with a flexible article having an opening and a slider operated fastener for closing said opening, of soft and pliable reenforcing material concealed in the walls of the article adjacent and extending lengthwise of the fastener, said material being molded on a form and thereby permanently shaped to conform to the shape of the article.

6. The combination with a flexible article having a lining and facing and having an opening closed by a slider operated fastener, of soft and pliable stiffening material adjacent and extending lengthwise of the fastener between the lining and facing and having the edges feathered so that the portions of lining and facing extending thereover have smooth exterior surfaces.

7. The combination with a flexible article having an opening and a slider operated fastener for closing said opening, of a strip of reenforcing material with tapered lateral portions extending lengthwise under the fastener, and a strip of reenforcing material at each side of the fastener each having a tapered portion at the inner side overlapping the tapered portion at the adjoining side of the first mentioned strip of reenforcing material.

8. The combination with a flexible article having an opening and a slider operated fastener for closing same, of a tongue having a central strip of reenforcing material therein, said tongue having the lateral portions secured to the material of the article at the respective sides of the opening for holding said strip of reenforcing material under the juncture line of the fastener.

9. In an interlocking fastener structure the combination of separable parts of flexible material, each having a series of fastener elements mounted on the edge thereof, a slider operable along the two series of fastener elements for interlocking and releasing same, said elements being closely arranged so as to afford a substantially continuous connection between the edges of the separable parts, and each of said parts of flexible material having

a pliant reenforcing of soft material extending therealong and concealed therein adjacent the series of fastener elements thereon.

10. The combination with a flexible article having separable parts of flexible material, and a detachable connection therefor, of a re-enforcing of soft pliable material concealed in the flexible material along and joining the detachable connection, said re-enforcing material being substantially flat and tapered in section to substantially feather edges so as to afford a smooth exterior surface for the article at the re-enforcing.

11. In an interlocking fastener structure the combination of separable parts of flexible material, each having a series of fastener elements along the edge thereof, a slider operable along the two series of fastener elements for interlocking and releasing same, said elements being closely arranged so as to afford a substantially continuous connection between the edges of the separable parts, and a plurality of strips of re-enforcing material arranged respectively under the interlocked position of the fastener and at each side thereof for avoiding excessive bending strain on the fastener.

12. The combination of a flexible article having separable parts and each of said parts having a series of fastener elements along the edge thereof, a slider operable along the two series of fastener elements for interlocking and releasing same, said elements being closely arranged so as to afford a substantially continuous connection between the edges of the separable parts, and a pliant re-enforcing of soft material concealed in the flexible material and extending along and adjacent to the series of fastener elements to protect the latter against excessive bending strain, said re-enforcing material being tapered in section substantially to a feather edge to afford a gradual increase in thickness of the flexible material and a smooth exterior surface at the re-enforcing.

13. The combination of a flexible article having separable side portions, a series of fastener elements on each side portion, a slider operable along the two series of elements for interlocking and releasing same, and a flexible member at the inner side of the fastener and having a reenforcing extending lengthwise under said fastener, said flexible member and reenforcing being shaped to normally assume a curvature lengthwise of the fastener.

14. The combination of a flexible article having separable side portions, a series of fastener elements on each side portion, a slider operable along the two series of elements for interlocking and releasing same, and a flexible member at the inner side of the fastener and having a reenforcing extending lengthwise under said fastener, said flexible member and reenforcing being shaped to

normally assume a curvature lengthwise and transversely of the fastener.

15. The combination of a flexible article having separable side portions, a series of fastener elements on each side portion and a slider operable along the two series of elements for interlocking and releasing same, said side portions when interlocked forming a connected structure of concave and convex form on both the outer and inner sides, and a flexible member at the inner side of said structure having a reenforcing extending lengthwise under the juncture line of the fastener elements and said member and re-enforcing being of concave and convex form corresponding to the inner side of the aforesaid connected structure.

16. The combination of a flexible article having separable side portions, a series of fastener elements on each side portion and a slider operable along the two series of elements for interlocking and releasing same, said side portions when interlocked forming a connected structure of concave and convex form on both the outer and inner sides, and a reenforcing of rubber composition on each of the said separable side portions adjacent the respective series of elements and shaped to conform to the concave and convex curvature of said connected structure.

17. The combination of a flexible article having separable side portions, a series of fastener elements on each side portion and a slider operable along the two series of elements for interlocking and releasing same, said side portions when interlocked forming a connected structure of concave and convex form on both the outer and inner sides, and a flexible member at the inner side of said structure, said side portions and flexible member being provided with reenforcing extending along the fastener and shaped to conform to the concave and convex form of the said connected structure.

18. The combination of a flexible article having separable portions, an elongated coiled fastener element on each separable portion having the adjoining convolutions thereof spaced apart to receive the convolutions of the other element therebetween and the convolutions of one of the elements being offset at their outer extremities to interlock with the convolutions of the other element, a slider operable along said coiled elements for interlocking and releasing same, and a flexible member extending under the said separable portions and having a reenforcing underlying the juncture line of the fastener elements.

19. The combination of a flexible article having separable portions, an elongated coiled fastening element on each separable portion having the adjoining convolutions thereof spaced apart to receive the convolutions of the other element therebetween and the

convolutions of one of the elements being offset at their outer extremities to interlock with the convolutions of the other elements, a slider operable along said coiled elements for interlocking and releasing same, and flexible reenforcing means combined with each of said separable portions and extending therealong adjacent the respective coiled fastener element to protect the latter against excessive bending.
